CAN RESEALING CLOSURE

Robert Sidney Lutzker, 90-12 212th St.,
Queens Village, N.Y. 11428

Filed Nov. 10, 1971, Ser. No. 197,637

Term of patent 14 years

Int. Cl. D9—07

U.S. Cl. D9—254

FIG. 1

FIG. 3

FIG. 4

FIG. 5

FIG. 6

FIG. 1 is a top plan view of a can resealing closure showing my new design;

FIG. 2 is a bottom plan view;

FIG. 3 is an end elevational view;

FIG. 4 is an end elevational view showing the end opposite that seen in FIG. 3;

FIG. 5 is a side elevational view, the opposite side being a mirror image of the side shown; and

FIG. 6 is a cross sectional view taken on the line 6—6 of FIG. 1.

I claim:

The ornamental design for a can resealing closure, substantially as shown and described.
